UNITED STATES PATENT OFFICE.

CONRAD KNOTH, OF NEWARK, NEW JERSEY, ASSIGNOR TO HYATT ROLLER BEARING COMPANY, OF HARRISON, NEW JERSEY, A CORPORATION OF NEW JERSEY.

DRAWN CAGE FOR ROLLER-BEARINGS.

1,183,651.

Specification of Letters Patent. Patented May 16, 1916.

Application filed August 20, 1915. Serial No. 46,416.

To all whom it may concern:

Be it known that I, CONRAD KNOTH, a citizen of the United States, residing at 173 Jelliff avenue, Newark, county of Essex, and 5 State of New Jersey, have invented certain new and useful Improvements in Drawn Cages for Roller-Bearings, fully described and represented in the following specification and the accompanying drawings, forming 10 a part of the same.

This invention relates to a so called "self-contained" set of rolls for a roller-bearing, the set comprising a cage to guide the rolls in their working position in the casing of the 15 bearing, and also hold them together in a unitary structure, which greatly facilitates their handling and transportation.

The object of the present invention is to produce a cheap and simple construction for 20 such roll-sets.

The invention was devised primarily for use with hollow rolls such as are shown formed by winding a strand of metal into spiral coils upon a mandrel, and the cage 25 may be readily engaged with the ends of such rolls by forming studs upon the cage to enter the bores of the rolls.

The cage consists of a cylindrical shell 30 with wings turned inwardly from longitudinal slots upon its periphery to fit the opposite sides of the rolls, and annular heads secured within the shell next the ends of the wings. The heads are provided with studs to enter the ends of the rolls, or rods may 35 be extended through the heads and the bores of the rolls, or any other means employed to prevent the rolls from falling out of the spaces between the wings.

The construction will be understood by 40 reference to the annexed drawing, in which—

Figure 1 is a longitudinal section of a bearing on a vertical line through the center of Fig. 2, with the shaft embraced by the 45 rolls; Fig. 2 is an end view of the "roll-set" with a shaft shown inside the rolls; Fig. 3 is a section of the cage, at the ends of the 50 rolls, on line 3—3 in Fig. 4; Fig. 4 is a side elevation of the cage with one end flanged and the other end left open to receive the 55 rolls and the heads; and Fig. 5 is an end view of one of the heads adapted to fit within the ends of the cage. Figs. 6 and 7 show tie-rods in the rolls.

55 A cylindrical casing α is shown in Fig. 1

with annular plates α' at its opposite ends through which the shaft or axle b may extend. The rolls c are proportioned to contact with the shaft and the inner side of the casing, and are shown each with a cylindrical bore c' . The periphery of the cage is made from a section of tubing and when finished possesses two collars d and e , with longitudinal slots f extending between the collars and having longitudinal bars g at the edges of the slots. The metal punched from the slots is bent inwardly from the edges of the bars g , forming wings h which are at suitable distances apart to fit opposite sides of the rolls, as shown in Fig. 3. Heads i are fitted 70 to opposite ends of the shell within the collars d and e , and are preferably formed upon their outer corners with rabbets j into which flanges e' can be bent from the said collars. The heads are shown with conical 75 studs k upon the inner side adapted to fit loosely within the bores of the rolls, and to hold them in the cage.

Fig. 1 shows the rolls adjusted between the heads, the shell fitted over the heads, and 80 the flanges e on both ends of the heads bent into the rabbets j , thus making the ends of the shell flush with the outer sides of the heads.

Fig. 4 shows the flange e' bent inwardly 85 upon the collar e , which would lock one of the heads in place against the ends of the wings h ; but the collar d is shown wholly cylindrical to permit the insertion of the rolls within the cage, and the application of 90 the other head, after which the edge of the collar d would be spun or flanged into the rabbet upon the second head.

Fig. 3 shows the wings h bent so that 95 their flat sides lie tangential to the cylindrical sides of the rolls c , but the guiding action of the cage may be performed just as well by bending the wings, as shown at h' in Fig. 6, so as to be radial to the surface of the roll instead of tangential.

Figs. 6 and 7 show one side of a cage having such construction for the wing, and also showing the heads m made perfectly flat and connected by tie-bars n which are extended through the rolls and shouldered to 105 enter holes in the heads, in which their ends n' are riveted, as shown in Fig. 7. Where the heads are thus held at a fixed distance apart, there is no necessity of flanging the ends of the cage, and the ends e^2 are there- 110

fore shown in Fig. 7 as plain cylindrical collars resting upon the peripheries of the heads, between which the bent wings h' would extend.

5 From the above description it will be understood that the essential feature of the cage is a cylindrical shell with wings turned inwardly from longitudinal slots upon its periphery, to contact with the cylindrical 10 sides of the rolls, and annular heads secured within the shell next the ends of the wings.

A short tongue t is projected laterally from each head near the edge, and is proportioned, as shown in Fig. 3, to fit between 15 two of the wings h upon the cage, thus holding the head from turning within the cage and serving to maintain the studs h opposite the centers of the rolls when inserted between the wings h .

20 The construction involves very few parts, which may all be cheaply made of sheet-metal, by stamping, and the cage operates most effectively to hold the rolls parallel to one another while in operation, and to 25 keep them within the cage in handling or transportation.

Having thus set forth the nature of the invention what is claimed herein is:

1. A cage for the rolls of a roller-bearing, 30 consisting of a cylindrical shell with wings turned inwardly from longitudinal slots upon its periphery to fit the sides of the rolls, and annular heads secured within the shell next the ends of the wings.

35 2. A cage for the rolls of a roller-bearing, consisting of a cylindrical shell with wings turned inwardly from longitudinal slots

upon its periphery to fit the sides of the rolls, rabbeted heads fitted within the shell near the ends of such wings and the ends of 40 the shell flanged into such rabbets to hold the heads in place.

3. A cage for the rolls of a roller-bearing, consisting of a cylindrical shell with wings turned inwardly from longitudinal slots 45 upon its periphery to fit the sides of the rolls, and annular heads secured within the shell next the ends of the wings and provided with studs to engage the ends of the rolls.

4. A cage for the rolls of a roller-bearing, consisting of a cylindrical shell having longitudinal slots in its periphery with wings from said slots bent inwardly in pairs at suitable distances to embrace the opposite 55 sides of the rolls, and heads secured within the ends of the shell, and provided each with a tongue to fit between two of the wings to hold the heads from rotation.

5. A roll-set for a roller-bearing, comprising a series of rolls with holes in the ends, a cylindrical shell with wings turned inwardly from longitudinal slots upon its periphery to fit the rolls upon opposite sides, and annular heads secured within the shell 60 next the ends of the wings, and provided with studs to engage the ends of the rolls, whereby the rolls are held permanently in the shell and are also guided when in operation.

70 In testimony whereof I have hereunto set my hand.

CONRAD KNOTH.
